DESIGN FOR A HAT

John Cavanagh, Norwalk, Conn., assignor to Hat Corporation of America, Norwalk, Conn., a corporation of Delaware

Application April 6, 1939, Serial No. 84,088

Term of patent 14 years

To all whom it may concern:

Be it known that I, John Cavanagh, a citizen of the United States, residing at Norwalk, in the county of Fairfield and State of Connecticut, have invented a new, original, and ornamental Design for Hats, of which the following is a specification, reference being had to the accompanying drawing, forming a part thereof, and in which:

Fig. 2 is a fragmentary perspective view of the hat brim.

The dominant features of my design are illustrated in solid black lines in the drawing.

I claim:

The ornamental design for a hat, substantially as shown and described.

JOHN CAVANAGH.
